CLAIM

The ornamental design for the vented finish bead, as shown and described.

DESCRIPTION

FIG. 1 is a top, front perspective view of a vented finish bead showing our new design;

FIG. 2 is a front view of the vented finish bead;

FIG. 3 is a back view of the vented finish bead;

FIG. 4 is an enlarged left side view of the vented finish bead;

FIG. 5 is an enlarged right side view of the vented finish bead;

FIG. 6 is a top plan view of the vented finish bead;

FIG. 7 is a bottom side view of the vented finish bead; and, FIG. 8 is a bottom, front perspective view of the vented finish bead.

The broken lines in the drawings illustrate portions of the vented finish bead that form no part of the claimed design.
